UNITED STATES PATENT OFFICE.

HERBERT M. FRIENDLY AND ARCHIBALD E. BURNS, OF PORTLAND, OREGON; SAID BURNS ASSIGNOR TO SAID FRIENDLY.

TOLL TELEPHONE SWITCHING APPARATUS.

1,342,260.

Specification of Letters Patent. Patented June 1, 1920.

Application filed June 15, 1915. Serial No. 34,182.

To all whom it may concern:

Be it known that we, HERBERT M. FRIENDLY and ARCHIBALD E. BURNS, residents of Portland, Multnomah county, Oregon, have invented certain new and useful Improvements in Toll Telephone Switching Apparatus, of which the following is a specification.

Our invention relates to improvements in apparatus, circuit systems, and methods of operation in connection with toll telephone switching apparatus.

A feature of this invention is to provide means and methods whereby any one of three toll lines terminating or entering at an interconnecting or common point may each be connected with any one of the remaining two lines through the agency of electromagnetic devices at the said common point, actuated by current from remote stations on said lines under independent control of operators at said stations.

Further, a feature of our invention relates to the means and methods whereby the calling station may signal the called station by the well known method of so called ringing, or other means.

Further, a feature of our invention relates to means whereby signals are displayed at a common point to indicate to the operator at the said common point the fact that a through switch or service is being made between two of the lines entering said common point, and to especially indicate which lines are interconnected thus.

Further, a feature of our invention provides for introducing a repeating coil by automatic process when any predetermined line is interconnected with another line.

Further, a feature of our invention is to disassociate signals and springjacks at the common point when certain predetermined lines become interconnected.

There are many other features.

Representation of apparatus in the accompanying drawings is diagrammatic and conventional and therefore does not purport to represent actual structural details.

Our invention is subject to wide changes and adaptations in applying it to practical uses by those skilled in the art to which it belongs without departing from its scope. The descriptions and drawings therefore refer to one of many applications and adaptations of our invention which applications

and adaptations are shown and described for purposes of illustration and elucidation only.

In the accompanying drawings:

Figure 1 is a diagrammatic representation of equipment of a toll board at a station designated station A, Fig. 7, on a line designated line 1. Terminals of this equipment, A and B, correspond to similar designations in Fig. 7.

Fig. 2 is a diagrammatic representation of equipment at a toll board at a station designated station B, Fig. 7, on a line designated line 2. Terminals of this equipment, C and D, correspond to similar designations in Fig. 7.

Fig. 3 is a diagrammatic representation of equipment at a toll board at a station designated station C, Fig. 7, on a line designated line 3. Terminals of this equipment, 75 55 and 56, correspond to similar designations in Fig. 7.

Fig. 4 is a diagrammatic representation of equipment at a toll board at a station designated station D, Fig. 7. The terminals 80 of this equipment K, L, M, N, O, P correspond to similar designations in Fig. 5. An agency of said equipment is to enable operators at the stations A, B and C to obtain, at will, communication with either one of 85 the other said stations, or any stations on the said lines.

Fig. 5 is a part of the circuit at station D. The terminals E, F and G, H, I and J correspond to the same letters in Fig. 4, 90 with a prime added. Terminals B''' and G''' correspond to B'' and G'' respectively, Fig. 4. Terminals K, L, M, N, O, P correspond to the same letters in Fig. 4, with a prime added. It is possible to have the 95 apparatus in Figs. 4 and 5 independent one of the other and connected by detachable connections between the above terminals.

Fig. 6 is a diagrammatic representation of the essential elements of a common form 100 of cord circuit suitable for connecting the springjacks shown with springjacks of independent lines, thus interconnecting the lines.

The methods of accomplishing the functions constituted in the represented form 105 of our invention may be outlined as follows: Each station is provided with two sources of current—one having its positive pole grounded, therefore adapted to pro- 110

ject a negative or minus current from its free terminal, and the other source of current having its negative pole grounded and therefore adapted to project positive or plus current from its free terminal. For convenience of description we will refer to negative current as minus current and positive current will be referred to as plus current. Each station, as station A, station 10 B and station C, is provided with three springjacks associated with the line extending to the common station D. Inserting a plug of a cord pair or set, as for instance P¹ of the pair shown in Fig. 6, in springjack J², Fig. 1, will project minus current from battery B² derivedly to terminals A and B. One path will be by way of upper winding of repeating coil C¹ through contacts 13—12. The other path will be by 15 way of lower winding of said repeating coil and contacts 16—17. Inserting said plug in springjack J³, will project plus current from battery B¹ derivedly to terminals A and B. One path will be by way of 20 upper winding of repeating coil C³ through contacts 26—25. The other path will be by way of lower winding of said repeating coil and contacts 29—30. This current will enter station D in parallel over 25 line 1 to terminals K and L respectively, station D, reaching ground G⁷ through center of repeating coil C¹² by way of polarized relay R²⁷. Designations to the right of said relay denote the direction of movement of the right end of its armature 30 when actuated by currents of polarities as designated at the arrows.

To illustrate the use of the apparatus shown, we will assume the operator at station A desires to call station B on line 2, the operator at said station A first inserts plug as P¹ into springjack J¹ and listens as in 35 previous case. If line 1 is free (there may be other stations on lines 1, 2 or 3 between the stations shown and station D, or there may be stations beyond or on extensions or legs of the respective lines), the operator removes plug from said springjack J¹ and inserts it into springjack J². Contacts 12—13 and 17—16 are made by the mechanical action of springjack springs J¹⁴ and J¹⁵, which connect the line conductors through 40 the center of repeating coil winding C¹ to minus battery B², causing minus current to flow over the line 1 to terminals K and L, Fig. 5; through center of repeating coil winding C¹²; through polarized relay R²⁷ to ground G⁷, causing said relay R²⁷ to operate in the indicated minus direction. This closes a circuit from ground G⁷ through contacts 208—207 to contact 195, and also through relay R²² to battery B⁷. Upon energization of relay R²² current flows 45 through contacts 195—194 through relay R²³ to battery B⁷, actuating said relay R²³. A circuit is also established from contact 208 through contacts 196—197; through relay R²⁴, to battery B⁷, the current causing 50 said relay to operate. Contacts 207—208 are broken, opening the circuit of relays R²² and R²³ and allowing them to restore to normal. Contacts 196—197 open, deenergizing relay R²⁴, which starts to restore to normal 55 but is now prevented by the action of the latch 326 on the arm 327. All the contacts of relay R²⁴ are adjusted to allow of a slight motion without breaking, consequently, re- 60

desired. Upon the response of the operator at station D, by inserting a plug similar to P¹ into springjack J¹⁴ or J¹⁵, Fig. 5, a circuit is established from the ground on the sleeve of the plug; through sleeve 70 of springjack; through relay R²⁹, to battery B⁷, the current flowing actuates relay R²⁹ and incidentally disassociates the line signal device D⁴ by opening contacts 242—243 and 244—245; closing contacts 241—241'. This completes a circuit from battery B⁷ through lamps 250 and 252 in multiple; through contacts 241—241' to ground G⁷, glowing the lamps. The glowing of the lamps will indicate to the other operators 80 at station D that the line is in use at said station. After manipulating the listening key k², a telephonic circuit is established from terminals K and L through tip and sleeve of springjack; through tip and ring 85 of the plug; through contacts 301—302 and 304—303; through contacts 307—306 and 210—311. Other operations of establishing connections to independent lines by means of the companion plug P² are well known 90 in the art.

Assuming that operator at station A on line 1 desires to call station B on line 2, the operator at said station A first inserts plug as P¹ into springjack J¹ and listens as in 95 previous case. If line 1 is free (there may be other stations on lines 1, 2 or 3 between the stations shown and station D, or there may be stations beyond or on extensions or legs of the respective lines), the operator removes plug from said springjack J¹ and inserts it into springjack J². Contacts 12—13 and 17—16 are made by the mechanical action of springjack springs J¹⁴ and J¹⁵, which connect the line conductors through 100 the center of repeating coil winding C¹ to minus battery B², causing minus current to flow over the line 1 to terminals K and L, Fig. 5; through center of repeating coil winding C¹²; through polarized relay R²⁷ to ground G⁷, causing said relay R²⁷ to operate in the indicated minus direction. This closes a circuit from ground G⁷ through contacts 208—207 to contact 195, and also through relay R²² to battery B⁷. Upon energization of relay R²² current flows 105 through contacts 195—194 through relay R²³ to battery B⁷, actuating said relay R²³. A circuit is also established from contact 208 through contacts 196—197; through relay R²⁴, to battery B⁷, the current causing 110 said relay to operate. Contacts 207—208 are broken, opening the circuit of relays R²² and R²³ and allowing them to restore to normal. Contacts 196—197 open, deenergizing relay R²⁴, which starts to restore to normal 115 but is now prevented by the action of the latch 326 on the arm 327. All the contacts of relay R²⁴ are adjusted to allow of a slight motion without breaking, consequently, re- 120

lay R²⁴ is to all operative purposes in an operated position. Current to ground G⁷ on contact 201 is connected with contacts 200—199—198, glowing busy or guard lamps 247, 249, 251, 253 and 255. Line No. 1 is now connected with line No. 2 as follows: inductively through the repeating coil windings C¹², C¹¹; through contacts 202—203 and 204—205; to line terminals M and N to toll line No. 2; to terminals C and D, station B; through springjack contacts 35—34 and 32—33, to line signal device D². The operator at station A signals by manipulating ringing key k⁵. Signaling current flows from generator Z² through contacts 6—7 and 11—10 to repeating coil winding C²; thence inductively to companion winding C¹; thence over circuit traced above to line signal device D², causing it to display. The operator at station B responds by inserting plug as P¹ into springjack J⁴, incidentally cutting off the line signal device D² and establishing a telephonic connection over the tip and ring of plug, tip and ring of springjack to line, and thence to station A as traced above. Relays R²⁸ and R³⁰ are actuated from same conductor as lamp 247 and actuate simultaneously with the glowing of said lamp, incidentally dissociating springjacks J¹⁴, J¹⁵ and J¹⁶, J¹⁷ by the opening of contacts 237—238, 239—240 and contacts 262—263 and 264—265 respectively. Subsequent operations of establishing a connection to independent lines follow the methods well known and common in the telephone art and need not be described.

need not be described.

When the operator at station A removes the said plug at the completion of the service, the current on the line and through relay R^{27} is broken, relay R^{27} restores to its normal position as drawn. Current now flows from ground G' through contacts 225-224; through contacts 206-207, to relay R^{22} . After relay R^{22} operates current flows through contacts 195-194 through relay R^{23} to battery B' . This actuates relay R^{23} and trips the latch 326, thus releasing relay R^{24} , which restores to its normal position as shown in the drawing. This incidentally opens contacts 206-207, deenergizing relays R^{22} and R^{23} , which also restore to their normal position as shown in the drawing. The apparatus is then ready for another call.

Since there are six sets of relays in Fig. 4 similar to those whose action is described above, and since the actions are almost identical in all, the above description may be applied to all. Therefore, for the sake of brevity and clearness and for convenience in making references, the similar relays and contacts are arranged in a parallel column below. Any difference in action will be noted in each particular case. It is not

necessary, however, to refer to this table if the action of the set of relays described is kept in mind, as the corresponding relays can be readily traced from the drawings.

Con- nection.	Re- lay.	Con- tacts.	Re- lay.	Re- lay.	Re- lay.	Lamps.	Lamps.	Lamps.
Line 1 to 2.	R ²⁷	228-229	R ²²	R ²³	R ²⁴	249	253	247
Line 1 to 3.	R ²⁷	222-223	R ²¹	R ²⁵	R ²⁶	251	255	248
Line 2 to 3.	R ¹⁹	189-190	R ¹⁴	R ¹⁵	R ¹⁶	249	251	259
Line 2 to 1.	R ¹⁹	183-184	R ¹³	R ¹⁷	R ¹⁸	253	255	246
Line 3 to 1.	R ¹²	143-144	R ⁷	R ⁸	R ⁹	249	251	257
Line 3 to 2.	R ¹²	149-150	R ⁶	R ¹⁰	R ¹¹	253	255	247

Assuming that the operator at a station A on line 1 desires to call station C on line 3, the operator at said station A inserts plug 85 as P^1 into springjack J^1 and listens in as in the previous case. If line 1 is free, the said operator removes plug from said springjack and inserts it into springjack J^3 , incidentally connecting line 1 with plus battery from the 90 center of repeating coil winding C^3 through contacts 26-25 and 29-30 to line; over line 1 to terminals K and L; to relay R^{27} . Relay R^{27} operates in the indicated plus direction followed by dependent relays R^{21} , 95 R^{25} and R^{26} in sequence, R^{26} being held in its operated position.

operated position. A telephonic circuit may be traced from springjack J^3 through contacts 26—25 and 29—30, as above to line 1; over line 1 to terminals K and L; inductively through repeating coil windings C^{12} and C^{11} ; through contacts 215—216 and 217—218; through contacts 232—233 and 236—235; to terminals O and P, to line 3; over line 3 to terminals 55 and 56; to tip and ring of springjacks J^8 and J^9 and through contacts 111—110 and 113—112, to signal device D^3 . The operator at station A signals by manipulating key k^6 , which connects generator Z^2 through contacts 19—20 and 23—24 to repeating coil winding C^4 ; thence through companion winding C^3 of said coil to terminals A and B of line 1. The operator at station C responds by inserting a plug as P^1 into springjack J^8 or J^9 . Current flows in circuit traced from grounded sleeve of said plug through sleeve of said springjack; through relay R^5 actuating it and incidentally disassociating the line signal device D^3 at contacts 110—111 and 112—113. Lamps 86, 87, 88, 89, 90 and 91 are caused to glow by the closing of contacts 108—109. The subsequent operations of establishing a connection to an independent line through the agency of the switching cord set shown in Fig. 6, are those in common use and well known in the art and thus require no description. The release to normal condition of the interconnected lines is accomplished 13

by the withdrawing of the said plug from springjack J^8 .

Assuming that an operator at station B on line 2 desires to call station D, the operator at station B will insert plug as P^1 into springjack J^4 . Subsequent operations including the responding of station D are the same as described for station A calling said station D.

- 10 Assuming that an operator at station B on line 2 desires to call station C, the operator at station B will insert plug as P^1 into springjack J^5 . Minus current will flow from battery B^4 through repeating coil winding C^5 ; through contacts 42-41 and 38-37 to terminals C and D of line 2; thence over line 2 to terminals M and N; through relay R^{19} to ground G^7 , actuating said relay R^{19} in the indicated minus direction. Relays R^{14} , R^{15} and R^{16} operate in sequence similar to previous description relating to relays R^{22} , R^{23} and R^{24} , relay R^{16} being held in its operated position. A telephonic circuit may be traced from the terminals M and N through condensers 153 and 154; through contacts 164-165 and 166-167; through contacts 232-233 and 235-236 to line terminals O and P; over line 3 to terminals 55 and 56; thence as previously traced through line signal device D^3 . The operator at station B signals with key k^1 . The signal current passes inductively through repeating coil winding C^6 and C^5 and current circuit is traced as before to line signal device D^3 , causing it to display. Subsequent operations are the same as described in description of station A calling station C.

- Assuming that an operator at station B on line 2 desires to call station A on line 1, the operator at said station B will insert plug as P^1 into springjack J^6 . Plus current will flow from battery B^3 through repeating coil winding C^7 ; through contacts 45-44 and 48-49; to terminals C and D of line 2; over line 2 to terminals M and N; through relay R^{19} to ground G^7 ; causing relay R^{19} to operate in the indicated plus direction. Relays R^{13} , R^{17} and R^{18} operate in sequence similar to that of previous description, relay R^{18} being held in its operated position. The telephonic circuit may be traced from terminals M and N through condensers 153 and 154; through contacts 176-177 and 178-179 to terminals L and K of line 1; thence to terminals A and B, etc. Subsequent operations are the same as described in description of station B calling station C.

- Assuming that an operator at station C on line 3 desires to call station A, the operator at station C will insert plug as P^1 into either of springjacks J^{10} or J^{11} . Current will flow in circuit from grounded sleeve of plug; through sleeve of springjack; through relay R^4 ; through relay R^2 to battery B^6 ,

and also through contacts 63-64 and 62-61; through relay R^3 to battery B^6 , causing relays R^2 , R^3 and R^4 to operate. Minus current flows from battery B^5 through contacts 79-80 to center of repeating coil winding C^{10} ; through contacts 68-67 and 70-71; to terminals 55 and 56 of line 3; to line terminals O and P; through relay R^{12} to ground G^7 , actuating relay R^{12} in the indicated minus direction. Relays R^7 , R^8 and R^9 operate in sequence, etc., relay R^9 being held in its operated position. Relay R^{20} also operates through closing of contacts 122-123, introducing repeating coil windings C^{13} and C^{14} by making of contacts 234-235 and 231-232. The telephonic circuit may be traced from line terminals O and P through contacts 234-235 and through repeating coil winding C^{14} ; thence inductively to winding C^{13} ; through contacts 131-132; through condensers 151 and 152; through contacts 124-125 and 126-127, to terminals K and L of line 1, to terminals A and B, etc., as described in description of station B calling station A. The operator at station C signals by manipulating key k^1 . Signal current will flow from generator Z^1 through contacts previously described through tip and ring of plug; through tip and ring of springjack; through terminals 60-59 and 58-57; through relay R^1 , causing its armature to vibrate in conformance with alternations of signaling current. This opens contacts 63-64 and 62-61 alternately and allows relay R^3 to restore to its normal position during the duration of the time signaling current is applied. Signaling current then flows through contacts 74-75 and 77-78; through winding C^9 of repeating coil; thence inductively to winding C^{10} ; through contacts 67-68 and 69-70 to line terminals 55 and 56; thence over line 3 to terminals A and B, etc., as previously traced to line signal device D^1 . Subsequent operations are the same as described in description of station B calling station A.

Assuming that an operator at station C on line 3 desires to call station B, the operator at station C will insert plug as P^1 into springjack J^{12} or J^{13} . Current will flow in circuit from grounded sleeve of plug; through sleeve of springjack; through relay R^2 to battery B^6 , causing said relays R^2 and R^3 to operate as in the last description above. It will be noted that the only difference is that relay R^4 does not operate, and with this exception the description of signaling and the course of telephonic currents may be applied to this case. Plus current flows from battery B^6 through the center of repeating coil windings C^{10} , etc., as previously traced to line, and through relay R^{12} to ground G^7 , causing relay R^{12} to operate.

- ate in the indicated plus direction. Relays R⁶, R¹⁰ and R¹¹ operate in sequence, as in similar previous description; likewise relay R²⁰ will operate, relay R¹¹ being held in its operated position. A telephonic circuit may be traced through repeating coil windings C¹³ and C¹⁴, as in the last description above; thence through condensers 151—152; through contacts 136'—137 and 138—139, 5 to the terminals M and N of line 2; over line 2 to terminals C and D; to springjacks J⁴ and signal device D². Subsequent operations are the same as described in description of station A calling station B.
- 10 15 Assuming that operator at station D desires to call station A, the operator at station D will insert plug as P¹ into either of springjacks J¹⁴ or J¹⁶. Current will flow in circuit from grounded sleeve of plug; through sleeve of springjack; through relay R²⁰, actuating said relay and incidentally disassociating signal device D⁴ by opening of contacts 242—243 and 244—245. The operator at station D signals with key 20 25 k¹ as previously described. The telephonic circuit may be traced from tip and ring of springjack through contacts 239—240 and 238—237 to terminals K and L of line 1; over line 1 to terminals A and B; thence to signal device D¹. Subsequent operations at 30 35 station A are the same as described in description of station B calling station A.
- Assuming that operator at station D desires to call station B, the operator at station D will insert plug as P¹ into either of springjacks J¹⁶ or J¹⁷, causing relay R³¹ to operate incidentally disassociating signal device D⁵ from line 2. The telephonic circuit may be traced from tip and ring of 40 45 springjack through contacts 264—265 and 262—263 to terminals M and N of line 2; over line 2 to terminals C and D; thence to signal device D². Subsequent operations at station B are the same as described in description of station A calling station B.
- Assuming that operator at station D desires to call station C, the operator at station D will insert plug as P¹ into either of springjacks J¹⁸ or J¹⁹ causing relay R³² to 50 55 operate, thus disassociating signal device D⁶ from line 3. The telephonic circuit may be traced from tip and ring of springjack; to terminals O and P of line 3; over line 3 to terminals 55 and 56; thence to signal device D³. Subsequent operations at station C are the same as described in description of station B calling station C.
- Two springjacks are shown associated in each group of springjacks corresponding to 60 the three functions of interswitching, Fig. 3. It is not necessary to limit the number to two springjacks in each group, but that any plurality of springjacks can be employed as found convenient to permit access 65 to lines by a number of separated operators at any station. The same applies to the springjacks shown in Fig. 5.
- Also, the signals shown may be the common form of lamp signal or electromagnetic signal. These may be changed within wide 70 limits if found desirable.
- Also, in the foregoing specification mention is made of the current passing over the lines 1, 2 and 3 in parallel. It is not essential that the currents for operating the 75 various relays shall pass over both wires of the line, but by employing well known methods one limb of the circuit only may be employed to convey these currents, leaving the remaining limb in each case for other uses. 80
- Having thus described our invention, what we claim as new and desire to secure by United States Letters Patent is:
1. The combination of a plurality of lines entering a common station; a remote station 85 on each of said lines; as many springjacks connected to a said line at each of said remote stations as there are lines entering said common station; a switching plug at each station adapted to use in said springjacks; means whereby inserting said plug into any of said springjacks will cause the line with which it is associated to become connected with a predetermined line entering the common station; a springjack at 90 each said station for service to the common station.
  2. The combination of a plurality of lines entering a common station; a remote station 100 on each of said lines; as many springjacks connected to a said line at each said remote stations as the number of lines it is desired to connect a said line with, line connecting relays at the common station; means at each said remote station for causing the actuation 105 of a relay at said common station associated with the line leading from the calling remote station and corresponding to a said springjack, said relay adapted to connect said calling line to a predetermined called 110 line entering the common station.
  3. The combination of three lines entering a common station; remote stations on said lines; three springjacks associated with said lines at each said remote station; line 115 connecting relays at the common station, a first said springjack adapted upon a switching plug registering with same to cause a first relay at said common station to actuate to close a telephonic circuit between said line and a first predetermined line of said lines; a second of said springjacks adapted upon a switching plug registering with same to cause a second relay at said common station to actuate to close a telephonic circuit 120 between said line and a second predetermined line of said lines; a third of said springjacks adapted for independent service on the line leading to said springjack.
  4. A plurality of lines entering a common 125

- station; a remote station on a first line; springjacks at said remote station corresponding to lines adapted to be connected with said first line; a first relay at said common station under control of said remote station, a second relay at said common station controlled by the first relay, a third relay controlled by the second relay adapted to connect said first line with a predetermined line entering said common station, the actuation of said third relay causing the said second relay to restore to normal position, the second relay in turn incidentally deenergizing said third relay, and a mechanical connection between the first and second relays for holding the first relay in energizing position with the lines connected.
5. A plurality of lines entering a common station, a remote station on the first line, a polarized relay at said common station differently operable for connection with either one of two other lines, two independently operable line connecting relays for connecting the first line with said two other lines and actuated according to the operation of the polarized relay, means for mechanically locking the line connecting relays in actuated position, and means for thereafter interrupting the energizing circuit of the 80 locked relay.
6. A plurality of lines entering a common station; a remote station on a first said line; a first relay at said common station under control of said remote station, a second relay at said common station controlled by the first, a third relay controlled by the second relay and adapted to connect said first line with a predetermined line entering said common station, the actuation of said third relay causing the said second relay to restore to normal position, the said second relay in turn incidentally deenergizing said third relay; and a mechanical connection between said second and third relays for holding the third relay in energizing position with the lines connected.
7. At a connecting point a first relay under control of a remote station; a second relay under control of said first relay; a third relay under control of said second relay, said third relay adapted to cause two predetermined lines to be connected together, said third relay also adapted to cause said second relay to return to normal position and said second relay adapted to in turn cause said third relay to become deenergized upon said second relay returning to normal position, said mechanical locking device so registering that said third relay is retained in an operated position upon said second relay returning to normal position.
- 50 5. A plurality of lines entering a common station; a remote station on a first said line; a first relay at said common station under control of said remote station, a second relay at said common station controlled by the first, a third relay controlled by the second relay and adapted to connect said first line with a predetermined line entering said common station, the actuation of said third relay causing the said second relay to restore to normal position, the said second relay in turn incidentally deenergizing said third relay; and a mechanical connection between said second and third relays for holding the third relay in energizing position with the lines connected.
- 55 7. At a connecting point a first relay under control of a remote station; a second relay under control of said first relay; a third relay under control of said second relay, said third relay adapted to cause two predetermined lines to be connected together, said third relay also adapted to cause said second relay to return to normal position and said second relay adapted to in turn cause said third relay to become deenergized upon said second relay returning to normal position, said mechanical locking device so registering that said third relay is retained in an operated position upon said second relay returning to normal position.
- 60 5. A plurality of lines entering a common station; a remote station on a first said line; a first relay at said common station under control of said remote station, a second relay at said common station controlled by the first, a third relay controlled by the second relay and adapted to connect said first line with a predetermined line entering said common station, the actuation of said third relay causing the said second relay to restore to normal position, the said second relay in turn incidentally deenergizing said third relay; and a mechanical connection between said second and third relays for holding the third relay in energizing position with the lines connected; means at said remote station for causing a second actuation of said first relay which in turn will cause the actuation of said second relay, said latter actuation 65 destroying the effective relation of the said

mechanical device so said third relay will return to normal position with said lines unconnected.

8. At a connecting point a first relay under control of a remote station; a second relay under control of said first relay; a third relay under control of said second relay, said third relay adapted to cause two predetermined lines to be connected together, said third relay also adapted to cause said second relay to return to normal position and said second relay adapted to in turn cause said third relay to become deenergized upon said second relay returning to normal position; a mechanical device between said second and third relays which will hold said third relay in an actuated position with lines connected; means at said remote station for causing the said third relay to return to normal.

9. At a connecting point a first relay under control of a remote station; a second relay under control of said first relay; a third relay under control of said second relay, said third relay adapted to cause predetermined lines to be connected together, said third relay also adapted to cause said second relay to return to normal position and said second relay adapted to in turn cause said third relay to become deenergized upon said second relay returning to normal position and a mechanical device between said second and third relays which will hold said third relay in an actuated position with lines connected.

10. A first polarized relay adapted to close independent circuits responsive to each polarity of energizing current applied thereto; a second relay under control of said first relay; a third relay under control of said second relay; a mechanical locking device forming a part of the moving elements of said second and third relays; said second relay adapted to return to normal position upon the actuation of said third relay and said third relay adapted to in turn deenergize upon said second relay returning to normal position, said mechanical locking device so registering that said third relay is retained in an operated position upon said second relay returning to normal position.

11. A first polarized relay adapted to close independent circuits responsive to each polarity of energizing current applied; a second relay under control of said first relay; a third relay under control of said second relay; a mechanical device forming a part of the moving elements of said second and third relays; said second relay adapted to return to normal position upon the actuation of said third relay and said third relay adapted to in turn deenergize upon said second relay returning to normal position, said mechanical device so registering that said third relay is retained in an op- 130

- erated position upon said second relay returning to normal position, said first relay adapted upon energizing with reversed polarity to reactuate said second relay and release to normal position said third relay.
- 5 12. A first polarized relay adapted to close independent circuits responsive to each polarity of energizing current applied; a second relay under control of said first relay; a third relay under control of said second relay; a mechanical device forming a part of the moving elements of said second and third relays; said second relay adapted to return to normal position upon the actuation 10 of said third relay and said third relay adapted to in turn deenergize upon said second relay returning to normal position, said mechanical device so registering that said third relay is retained in an operated position upon said second relay returning to normal position, said first relay adapted upon energizing with reversed polarity to reactuate said second relay and release to normal position said third relay, the said 15 third relay adapted to interconnect a plurality of predetermined lines during the time it is in an actuated position.
13. The combination of a plurality of lines entering a common station; a remote 20 station on a first said line; means at said remote station for applying current of a first and a second polarity at will; a relay at said common station differently responsive to said polarities of current, said relay controlling a second relay upon its actuation conforming to said first polarity, said second relay in turn controlling a third relay, said third relay in turn causing said second relay to return to normal position 25 upon the actuation of said third relay; a device forming a part of second and third relays for retaining said third relay in an actuated position mechanically upon the return to normal position of said second relay and the incidental deenergization of said third relay thereby; a circuit relationship between the contacts of said relays such that when said second current polarity is applied to said relay causing its actuation conforming therewith said second relay will actuate to mechanically release to normal position 30 said third relay.
- 35 14. The combination of a plurality of lines entering a common station; a remote station on a first said line; means at said remote station for applying current of a first and a second polarity at will; a relay at said common station differently responsive to said polarities of current, said relay controlling a second relay upon its actuation conforming to said first polarity, said second relay in turn controlling a third relay, said third relay in turn causing said second relay to return to normal position 40 upon the actuation of said third relay; a device forming a part of second and third relays for retaining said third relay in an actuated position mechanically upon the return to normal position of said second relay and the incidental deenergization of said third relay thereby; a circuit relationship between the contacts of said relays such that when said second current polarity is applied to said relay causing its actuation conforming therewith said second relay will actuate to mechanically release to normal position 45 said third relay.
- 50 15. The combination of three lines entering a common station; a remote station on a first said line; relays at the common station, means at said remote station for controlling a first relay at said common station which is adapted to connect together predetermined lines upon it being in an actuated position; a signal lamp at said common station and a second relay controlling access to said first line from said common station under control of said first relay, the said lamp adapted to glow and the said second relay adapted to prevent access to said line during the time said first relay is in an actuated position.
- 55 16. The combination of three lines entering a common station; a remote station on a first said line; relays at a common station, means at said remote station for controlling a first relay at said common station adapted to connect together predetermined lines upon it being in an actuated position; a signal lamp at said common station and a second and third relay controlling access respectively to said first line and the predetermined line with which it is adapted to be connected by said first relay, the said lamp adapted to glow and the said second and third relays adapted to prevent access to said first line and the line with which it is connected during the time said first relay is in an actuated position.
- 60 17. At a connecting point three lines adapted to be connected one with another at will; relays controlled over said lines for making such connection; three signal lamps controlled from said relays, each said lamp upon glowing indicating that a specific two lines are connected.
- 65 18. The combination of three lines entering a common station; relays on each said line for connecting the specific line with a predetermined line; signal lamps associated with the relays which will glow when two said lines are connected, each said lamp glowing being indicative of two definite lines being connected.
- 70 19. At a connecting point three lines adapted to be connected one with another at will through the agency of two relays on each line at said connecting points, the first

- of said relays adapted to connect its associated line to a second line and the second of said relays adapted to connect its line to a third line; three signal devices with a free 5 pole of each common to contacts of two said relays, mate contacts so disposed that the actuation of any said relay connecting any two lines will incidentally cause a said signal device to actuate indicative of which 10 two lines are connected.
20. At a connecting point a first line adapted to be connected to a second or third line at will through the agency of specific relays therefor; a second line adapted to be 15 connected to said first or said third line at will through the agency of specific relays therefor; said third line adapted to be connected to said first or said second line at will through the agency of specific relays 20 therefor; three signal devices so associated with auxiliary circuits of said relays that a specific said device will actuate upon any said relay actuating incidental to connecting any two lines, the actuation of a said 25 signal device indicating a connection between a specific two lines.
21. At a connecting point lines adapted to be connected, relays controlled over calling lines and each specific to the two lines 30 to be connected; a repeating coil, an auxiliary relay associated with a calling line adapted to introduce all the windings of the repeating coil into said line, said relay under control of the relay adapted to connect said line with a second line.
22. At a connecting point a calling line adapted to be connected to any one of a plurality of lines; means controlled over the calling line to effect such connection, a repeating coil, electro-magnetic means controlled over a calling line adapted to connect all the windings of the repeating coil 35 into said calling line, said means operative when said first line is connected with a predetermined line of said plurality of lines.
23. In a telephone system, a subscriber's telephone line terminating at a connecting station, spring jacks for the line at said station, a normally disconnected repeating

coil for said line, a plug ended cord circuit, and means responsive to the insertion of the plug into a spring jack to connect the repeating coil into the line circuit.

24. In a telephone system, a telephone line extending from an operator's station to an interconnecting station, a second telephone line 55 extending from the interconnecting station, spring jacks for the first line at the operator's station, a repeating coil for the first line, a plug ended cord circuit, means whereby the operator may connect with the near line through one spring jack and with the far line through another spring jack, and means whereby when connection is made with one of the two lines said repeating coil is connected into the line circuit.

25. In a telephone system, three telephone lines terminating at a common station, remote stations on each line, a calling signal 70 for each line at the common station, means at the common station controlled from a remote station for connecting the line of the remote station with either one of the other two lines and for disconnecting the calling 75 signals of the connected lines at the common station, and a signal lamp at the common station operative to indicate that a connection exists between the two lines.

26. In a telephone system a plurality of 80 lines entering a common station, relay mechanism for interlinking said lines interchangeably so as to connect any two lines, and lamp signals controlled by said relay mechanism at said common station, one 85 specific to each possible connection, each lamp indicating that its corresponding two lines are connected.

Signed by us at Portland, county of Multnomah, and State of Oregon, in the presence 90 of two witnesses, this fifth day of June, 1915.

HERBERT M. FRIENDLY.
ARCHIBALD E. BURNS.
